Attorney

Patented June 23, 1925.

UNITED STATES PATENT OFFICE.

GEORGE MEZEI, OF CLINCHCO, VIRGINIA.

PENCIL SHARPENER.

Application filed March 13, 1924. Serial No. 698,942.

To all whom it may concern:

Be it known that I, GEORGE MEZEI, a citizen of Hungary, residing at Clinchco, in the county of Dickenson and State of Virginia, have invented certain new and useful Improvements in Pencil Sharpeners, of which the following is a specification.

This invention relates to new and useful improvements in pencil sharpeners.

10 An important object of the invention is to provide a pencil sharpener which may be easily carried in a person's pocket and may conveniently be handled without any support other than the hands of the user.

15 A further object of the invention is to provide a pencil sharpener wherein a movable cutting element is provided and associated with the remaining portions of the device in such a manner that it may be easily and 20 quickly removed for sharpening the cutting edge.

A still further object of the invention is to provide a device of the above mentioned type which is of exceedingly simple construction, strong, and durable, and one that may be manufactured at a very nominal cost.

Other objects and advantages of the invention will be apparent during the course 30 of the following description.

In the accompanying drawing forming a part of this specification and in which like numerals are employed to designate like parts throughout the same.

35 Figure 1 is a side elevational view of the pencil sharpener embodying this invention,

Figure 2 is an end elevational view of the pencil sharpener shown in Fig. 1 and taken to illustrate its appearance when viewed 40 from the left hand end of Fig. 1,

Figure 3 is an end elevational view of the cutter illustrated in Fig. 1 and taken to illustrate the opposite end to that illustrated in Fig. 2,

45 Figure 4 is a top plan view of the pencil sharpener shown in Figs. 1 to 3 inclusive,

Figure 5 is a partly elevational view and partly sectional view of the pencil sharpener shown in the aforementioned figures,

50 Figure 6 is a transverse sectional view taken upon line VI—VI of Fig. 5, and

Figure 7 is a detail perspective view of the cutting element shown in assembled position in Figs. 1 to 5 inclusive.

55 In the drawing, wherein for the purpose

of illustration is shown a preferred embodiment of this invention, the numeral 5 illustrates a rectangularly-shaped body portion having integrally formed therein and at one end thereof a semi-conical-shaped groove 6. 60 The end of the body portion 5 having the semi-conical groove 6 formed therein is also provided with spaced pairs of circularly shaped lugs which are provided for forming portions of a hinge which will be described 65 at a later point. Secured to the underface of the rectangularly-shaped body portion 5 is a strap which is formed into a double loop 8 and is provided for receiving two of the fingers of the operator.

70 A skeleton guide frame 9 is provided with the hinge portions 10 which are secured to the aforementioned hinge portions 7 by means of the pintles 11, as best illustrated in Figs. 1, 2, 4 and 5. This skeleton guide frame consists of the spaced side arms 12 which carry the said bearing parts 10 at one end and are connected at the opposite end by the cross piece 13 which is provided with an annularly arranged clasp portion 14 80 which is intended to yieldably engage the transverse end edge of the rectangularly-shaped body portion 5 for retaining the said body portion and the skeleton guide frame in the respective positions illustrated in 85 Figs. 1 to 6 inclusive.

In Fig. 7 there is illustrated in detail a cutting element which consists of the plate portion 16 having the integral, angularly arranged lugs 17 formed at the four corners thereof. This plate 16 carries a depending, integrally formed cutting edge 18 which is arranged transversely of the cutout portion 19 formed in the plate 16 for the purpose of permitting the shavings cut by the edge 18 to be discharged from the device. Suitably secured to the top surface of the plate 16 is a strap which is formed into a loop 20 and is provided for receiving one of the fingers of the operator.

100 It will be seen by inspecting Figs. 1 to 5 inclusive that the skeleton guide frame 9 may be hinged in respect to the rectangularly-shaped body portion 5, after the clasp 14 has been disengaged from the edge 15, and the looped strap 20 may be inserted into the groove formed by the spaced side arms 12 of the skeleton guide frame 9. With the loop 20 in this position, the depending lugs 17 carried by the plate 16 will be arranged to 105 110

slidably engage the longitudinal edges of the rectangularly-shaped body portion 5. After the skeleton guide frame has again been secured to the rectangularly-shaped body portion 5, the operator may reciprocate the plate 16 for moving the cutting edge 18 longitudinally of the semi-conically-shaped groove 6 formed in the body portion 5. In Figs. 5 and 6, there is illustrated a pencil P positioned with its writing end received within the semi-conical groove 6. It will now be seen that when the operator reciprocates the plate 16 with its cutting edge 18 that the latter will cut shavings from the pencil P for sharpening the same.

It is now believed that the construction and operation of this pencil sharpener will be understood by those skilled in the art. It is, further, to be understood, that the form 20 of this invention herewith shown and described is to be taken as a preferred example of the same, and that various changes in the shape, size, and arrangement of parts may be resorted to without departing from the 25 spirit of the invention or the scope of the subjoined claims.

Having thus described the invention, I claim:—

1. A pencil sharpener comprising a plate 30 having at one end a semi-conical depression to receive one pencil end, said plate being provided with hinge eyes at each side of the base of said depression, a U-shaped plate having the legs of the U hinged to said

hinge eyes and carrying at its free end a 35 spring clip engageable with the end of the first plate remote from the hinge eyes, a knife supporting plate provided with lugs on each side and at each end, said lugs engaging the side edges of the first plate, a 40 knife carried by said knife supporting plate, and a handle projecting upwardly from the knife supporting plate between the legs of the U-shaped plate for reciprocating the knife supporting plate. 45

2. A pencil sharpener comprising a plate having at one end a semi-conical depression to receive one pencil end, said plate being provided with hinge eyes at each side of the base of said depression, a U-shaped plate 50 having the legs of the U hinged to said hinge eyes and carrying at its free end a spring clip engageable with the end of the first plate remote from the hinge eyes, a knife supporting plate provided with lugs on each 55 side and at each end, said lugs engaging the side edges of the first plate, a knife carried by said knife supporting plate, and a handle projecting upwardly from the knife supporting plate between the legs of the U-shaped plate for reciprocating the knife supporting plate, said handle being formed as a finger receiving loop and the first plate having a plurality of finger receiving loops extending downwardly from its under side. 60 65

In testimony whereof I affix my signature.

GEORGE MEZEI.
